UNITED STATES PATENT OFFICE.

JOSEPH W. SNELL, OF HAMILTON, ONTARIO, CANADA.

SIGN.

Application filed April 13, 1923. Serial No. 631,946.

To all whom it may concern:

Be it known that I, JOSEPH W. SNELL, a citizen of the United States, residing at Hamilton, in the Province of Ontario, Canada, have invented new and useful Improvements in Signs, of which the following is a specification.

This invention relates to metal signs, such as are used on automobiles, door-
10 plates and the like, and consists in a sign structure composed of a supporting bar and separate letter or character members, which can be assembled on the supporting bar as desired and then be rigidly secured
15 in place by a simple operation, so that there will be no danger of their rattling or becoming loose or displaced.

An object of the invention is to enable any desired word or set of numbers to be
20 easily assembled to form a desired sign which, when completed, will be as solid and rigid as if made of one integral piece of metal.

Another object is to provide means for
25 securing such a built-up sign to the license plate of an automobile, and to provide modified means for securing a plurality of such signs together to be used as an office or desk name-plate, and similar purposes.

30 The invention is illustrated in the accompanying drawing, in which—

Figure 1 is a face view of an automobile license plate or tag, with one of my improved letter signs secured to the top edge thereof.

Figure 2 is a vertical cross-section of the same on the line 2—2 of Figure 1.

Figure 3 is a horizontal section on the line 3—3 of Figure 1.

40 Figure 4 is a partial perspective view of the supporting member or bar.

Figure 5 is a perspective view of one of the letter members.

45 Figure 6 is a similar view of an end member of the sign, and

Figure 7 is a perspective view of a modified form of clip for securing two of the signs to a support.

50 In Figure 1, a license plate 1 of an ordinary type is shown, provided as usual with slots 2 for securing bolts. Above the plate 1, as shown, is mounted one of my adjustable letter or built-up signs 5, spelling the word "Cleveland," for example, and secured to the plate 1 by means of two sheet-metal clips 3, formed as shown

in Figure 2 and held to said plate by bolts 4, passed through slots 2 and holes or slots 11 in the clips.

The supporting member of the sign is best illustrated in Figure 4. It consists of a sheet metal bar 6, having its longitudinal edges bent over and inward to form flanges 7 and provided with a central longitudinal groove forming a bulge 8 on the same side as the flanges 7. The width of said bulge is immaterial and it may extend entirely across the bar from one flange to the other, if desired.

The letter or character members are best illustrated in Figure 5, in which it will be seen that each of these members is a short sheet-metal plate 9, bearing on its face the character, and having its upper and lower edges bent over, inward and back to form flanges 10. The flanges 10 are so shaped that they can be slid over the flanges 7 of the bar 6 and enclose the same, as shown in Figure 2, so that any desired combination of character members can be assembled on the bar or supporting member, which is cut to the required length, and then the thus loosely assembled sign is completed by applying pressure, preferably by rolls, to flatten down the interengaged flanges, and simultaneously flatten out the bulge 8, which naturally forces the flanges of the bar apart and binds the character members to it, the securing being further completed by the flattening of the combined edges, so that the whole forms a rigid structure and there will be no danger of rattling.

To complete the sign, end pieces 12, see Figure 6, are or may be used, they being made similarly to the character members, but being also provided with an end flange 13, in addition to the longitudinal flanges 14. The end piece, shown in Figure 6, has also an end tab or lug 15, by which the sign can be attached to a support, as when the sign is used on a house or door, for example. Where the clips 3 are used, the end pieces need not have these tabs 15. The clip shown in Fig. 2 and in dotted lines in Fig. 1 is for holding one of the signs only, as when it is used in connection with an automobile license plate, while the clip shown in Fig. 7 is used when two (or more) of the built-up signs are used together as a name-plate or the like. In this case, the ends of the clip 16 are bent over to form hooks 17 and 18 and the side

edges are cut out and slit as shown, the slit portions having their free ends bent over in opposite directions to form hooks 18, one cooperating with the hooks 18 at 5 the top end and the other with the hooks or flange 17 at the bottom end. If desired a lug 19 is left at the top end by which the assembled sign can be suspended.

Having thus described my invention, what 10 I claim is:

1. A built-up sign, comprising a supporting bar member having its longitudinal edges bent over and a central longitudinal bulge, individual character members having 15 their edges bent over to fit the edges of said bar, whereby pressure on said bulge and edges rigidly secures the parts together, and means to attach the sign to a support.

2. A sign composed of a bar having a central longitudinal bulge, and separate character members having flanges to slidably fit the edges of said bar, said members being adapted to be rigidly secured together by flattening out said bulge.

25 3. A name sign for automobiles, consisting of individual character members slidably assembled on a supporting bar, the latter having a central longitudinal bulge which, when flattened out, rigidly secures 30 said character members in place, and clips engaging the upper and lower edges of the sign and provided with means for attachment to a license plate.

35 4. A built-up sign, consisting of a backing bar having top and bottom flanges and a central bulge, character members having top and bottom flanges adapted to enclose said bar flanges and enable-said members to be assembled by sliding the character members 40 on said bar, end members having similar flanges to those of said character members and in addition each an end flange to en-

close the ends of said bar, the whole being made rigid by pressure applied to said bulge and to said interengaged flanges, and means 45 to secure the completed sign to a supporting structure.

5. A sign composed of a plurality of sheet metal members bearing symbols, the top and bottom edges of said members being bent or 50 curled over and inward, and a supporting or backing bar for said assembled members having a central longitudinal bulge, the top and bottom edges of said bar being bent over so as to slidably fit within the said edges of 55 said members, whereby the sign can be made into a rigid structure by compressing the said interengaged edges and simultaneously flattening said bulge.

6. A sign comprising a back bar slightly 60 curved transversely and having its longitudinal edges bent over, a plurality of character members having their edges bent over so as to slidably fit over said bar and be rigidly secured thereto by the folding down of the 65 engaged edges, and clips for mounting the sign on a support, each clip consisting of a strip having means for engaging the longitudinal edges of the sign.

7. A built-up sign, comprising two sup- 70 porting bars, a plurality of character members mounted on each bar and secured thereto by folding over the engaged longitudinal edges of said members and bar, and clips to hold said bars in rigid relation, each clip 75 consisting of a strip of metal having its ends bent over to form hooks and its side edges cut out and slitted, the slit portions having their free ends bent over in opposite directions to form hooks cooperating respectively 80 with said end hooks.

In testimony whereof I have hereunto set my hand.

JOSEPH W. SNELL.
